UNITED STATES PATENT OFFICE.

ROBERT C. SCHEMMEL, OF UNION CITY, INDIANA, ASSIGNOR TO THE BACKSTAY MACHINE & LEATHER COMPANY, OF UNION CITY, INDIANA, A CORPORATION OF INDIANA.

FINISHING WELT.

Application filed February 2, 1925. Serial No. 6,363.

To all whom it may concern:

Be it known that I, ROBERT C. SCHEMMEL, a citizen of the United States, residing at Union City, in the county of Randolph and State of Indiana, have invented certain new and useful Improvements in Finishing Welts; and I do hereby declare the following to be a full, clear, and exact description of the invention, such as will enable others skilled in the art to which it appertains to make and use the same.

My present invention relates to improvements in finishing welts such as used in trimming automobile bodies, tops, or interiors when required, other vehicles, furniture, etc., and contemplates more particularly stated, what is known to the trade as a "blind-nail" welt, wherein the attaching means is hidden by the welt itself when applied in operative position, as exemplified by U. S. Letters Patent No. 1,226,600, issued to me under date of May 15, 1917.

In the manufacture of welts of the character indicated, it is a matter of prime importance that they possess great flexibility to facilitate comparatively short turns, either in a horizontal or vertical direction, as the welt is applied to the more or less curved surfaces of the body or article in process of trimming.

It is therefore an object of this invention to produce in running lengths or yardage, a finishing welt which in itself serves to conceal the tacks or other fastening means, by which it is secured in place, and at the same time an article that is remarkably flexible to assist in turning corners without liability of "puckering".

A further object is the speedy, accurate and economical production of welts of the character indicated, employing an elastic body or core which assists in retaining the finished article in its normal applied position, by agency of the inherent elasticity of the core itself.

With the foregoing and other objects in view my present invention will now be particularly described, and hereinafter pointed out by the appended claims.

In the accompanying drawings which form part of this application for Letters Patent, and whereon corresponding reference characters indicate like parts in the several views:

Figure 1 is a perspective view, in section

at one end, of a fragment of welt embodying the present improvements;

Figure 2 is a relative enlarged cross sectional view of the improved blind-nail welt in process of application to an article 60 of manufacture, such for example, as the back of an automobile seat; and

Figure 3 is also a cross sectional view, corresponding with Figure 2, but showing the welt in its finished, applied position, and 65 the fastening tack concealed thereby.

Reference being had to the drawings and numerals thereon, 1 indicates an elastic flexible core, preferably of rubber molded to the desired or required cross sectional 70 shape, and 2 is a beading-cord of any suitable flexible material, but preferably of tightly twisted paper for economy of production. These two parallel members 1 and 2 are enclosed or encased in a wrapper of 75 suitable flexible material, preferably a unitary strip of leather, imitation leather, or fabric of any kind, either with or without a nap of mohair or plush according to requirements of the individual job to be 80 trimmed.

This wrapper or envelope starting at 3 encloses the core 1 to form a welt body 4 as clearly shown by the drawings, doubles upon itself as at 5, thus forming a two-ply 85 welt-base 6, thence encircles the cord 2 to form a bead 7, and terminates at 8 adjacent the starting point 3.

During the process of formation as aforesaid the elastic core 1 is stitched throughout 90 its entire length, as at 9 to and through the two underlying thicknesses of its wrapper, as shown, and in like manner that portion of said wrapper which encloses the aforesaid cord 2, is also stitched permanently together 95 as at 10 to complete the bead 7, as best shown by Figures 2 and 3 of the drawings.

This improved form of welt having been made substantially as shown and described, is applied by agency of flat headed tacks 100 such as 11, driven at intervals through the two-ply welt-base as indicated by Figure 2.

While the welt-base 6 is being drawn down to its final position as shown by Figure 3, the trimmer holds the welt-body 4 in 105 substantially the position indicated by Figure 2 under slight tension at its lower edge, so that when released the said body automatically and positively snaps down to the normal applied position of Figure 3 because 110

of the inherent elasticity of the core 1 itself, and while the present illustrations show the stitches 9 passing through the welt body 1, and through but one ply of the two-ply base 6, it is obvious that said stitches may, if desired, extend entirely through both of said base plies as the means of connecting said welt-body to the tack-receiving base, without in the least departing from the spirit of 10 this invention as set forth in the following claims.

This being the form and general construction of my present improved finishing welt, its use and operation will be quite apparent 15 from the foregoing, and further statement as to its well known uses is considered unnecessary.

Having thus described my invention what I now claim and desire to secure by Letters 20 Patent is:

1. A finishing welt of the blind-nail type including in combination a tack-receiving base, and an independent tack-concealing welt body permanently secured to said base 25 by fastening means passing through said body and spaced inwardly from the edge thereof, said fastening means connecting said welt-body to the base.

2. A finishing welt of the blind-nail type 30 including in combination a tack-receiving base, and an independent tack-concealing welt-body permanently secured to and hinged upon said base by fastening means passing through said body and spaced inwardly from the edge thereof, said fastening means connecting said welt-body to the base.

3. A finishing welt of the blind-nail type including in combination a tack-receiving base, and an independent tack-concealing welt-body having an elastic core permanently 40 secured to said base by fastening means passing through said body and spaced inwardly from the edge thereof, said fastening means connecting said welt-body to the base.

4. A finishing welt of the blind-nail type, 45 including in combination a tack-receiving base, and an independent tack-concealing welt-body having an elastic core hinged to said base by means of stitches passing through said elastic core and spaced inwardly from the edge thereof, said stitches connecting said welt-body to the base.

5. A finishing welt of the blind-nail type including in combination a tack-receiving base, an independent tack-concealing 55 welt-body permanently secured to said base by a line of stitches passing through said body and spaced inwardly from the edge thereof connecting said welt-body to the base, and a relatively fixed surface bead 60 parallel with the welt-body aforesaid.

6. A finishing welt of the blind-nail type including in combination a suitable base, an independent elastic welt-body permanently 65 hinged to said base by means of stitches passing through said body and spaced inwardly from the edge thereof connecting said welt-body to the base, whereby the welt-body automatically closes over the base aforesaid by reason of its inherent elasticity.

In testimony whereof I affix my signature.
ROBERT C. SCHEMMEL.
